United States Patent Office

Des. 219,991
Patented Feb. 23, 1971

219,991

SOAP LATHER GENERATOR

Donald A. De Vareo, Bay Village, Ohio, assignor to Sunbeam Corporation, Chicago, Ill., a corporation of Delaware

Filed Oct. 24, 1969, Ser. No. 19,693

Term of patent 14 years

Int. Cl. D6—01

U.S. Cl. D33—30

Fig. 4.

Fig. 6.

FIG. 1 is a front perspective view of a soap lather generator embodying my design;

FIG. 2 is a front elevational view thereof;

FIG. 3 is a right side elevational view thereof;

FIG. 4 is a top plan view thereof;

FIG. 5 is a sectional view taken along line 5-5 of FIG. 2; and

FIG. 6 is a fragmentary sectional view taken along line 6-6 of FIG. 2.

I claim:

The ornamental design for a soap lather generator, as shown.
